COMBINED SHUTTER AND AWNING

Edwin Terry, Miami, Fla.

Application December 7, 1934, Serial No. 756,520

3 Claims. (Cl. 20—59)

This invention relates to combined storm shutters and awnings for windows.

A primary object of the invention is to so construct such a combined shutter and awning that while it will be extremely simple and cheap to manufacture having a minimum number of parts, it will yet be equally as effective as more expensive and complicated structures of this character.

Another object is to construct an article of this character so that it may be opened and shut from within the house in a very few seconds and which may be opened to any degree or angle.

Another object is to construct a combined shutter and awning so that when in open position to form an awning a pivotally mounted lower portion will automatically drop to form a valance, and when the shutter is closed this valance will flatten out to form a shutter extension and be held by the body of the shutter against rattling.

Other and more specific features of the invention residing in advantageous forms and combinations of parts will hereinafter appear and be pointed out in the claims.

In the drawing illustrating the preferred embodiment of the invention:

Figure 1 is a perspective view of the device shown applied and in the position which it assumes when used as an awning;

Fig. 2 is a longitudinal vertical section with the device shown folded for use as a shutter in full lines and in open position for use as an awning in dotted lines; and

Fig. 3 is a rear elevation of the device detached.

In the embodiment illustrated a window frame 1 is shown having openings 2 extending thru the lower side rails thereof and reinforced by metal sleeves to receive the operating chains of the combined awning and shutter 10 constituting the invention.

Extending transversely of the frame 1 at its upper end is a cross bar 3 having at its outer edge a depending lip 4 with a recess 5 in rear thereof. The combined shutter and awning 10 has hinges 11 at its upper edge which are attached to the top cross bar 3 of the frame 1 to permit the combined shutter and awning to swing outwardly and inwardly, the upper edge of said device 10 being located within the recess 5 and its outer face adapted to abut the depending lip 4 to limit the outward swing of the awning, forming a stop therefor.

The combination shutter and awning is formed of a main or body section 12 with a smaller valance section 13 hinged at 14 to the lower end of section 12 and which is adapted by its weight to

swing downward into the position shown in Fig. 1 when the device is open to form a valance for the awning. The lower edge 12a of section or body 12 overlies the upper edge of section 13 when the device is arranged as a shutter as shown in Fig. 2 and said upper edge lies in a recess 15 of the lower cross bar of body 12 and is held thereby said overlapping body extension and prevented from rattling and also prevents the entrance of water and dust at this point. While I have shown and prefer to use the valance 13, it is not an essential and may be dispensed with when body portion 12 is made large enough to cover the entire opening.

These shutter members 12 and 13 are rigid and formed of any suitable material with cleats 15 or bars secured along their edges on their inner faces, the side members or cleats 20 of the body being cut out adjacent their inner edges to form guides for a U-shaped operating member 18 the cross bar 19 of which is of a length to permit the arms 17 to fit between the outer walls of the recessed portion of the side rails 20, see Fig. 3. The side rails of these members 12 and 13 are designed to lie flat against the window frame 1 when the shutter is closed with the edges of the 25 plate-like portions thereof overlying said frame to make a weather-tight connection between them.

Coiled springs 21 and 22 connect the upper cross bar 23 of section 12 with the cross bar 19 of the member 18 and exert their tension to force said device into open position for use as an awning. Keepers 24 are secured to the side rails 20 of member 12 and the cross bar 19 of member 18 is mounted to slide therein to prevent undue strain on the lip or stop 4 and to also prevent rattling of the shutter.

Chains 25 are attached to the lower ends of the side rails 20 of shutter member 12 and are threaded thru the openings 2 in the side rails 40 of the window frame 1 as shown in Fig. 2 and the links thereof may be engaged with hooks 26 on the frame to hold the shutter in closed position against the tension of the springs 21 and 22.

Assuming the shutter to be in closed position 45 as shown in full lines in Fig. 2 and held by engagement of one of the links of the chain 25 with the hook 26, but when released the springs 21 and 22 which have been under tension will tend to contract and lift section 12. As this 50 section rises the arms 17 of member 18 will force the section outwardly until stopped by engagement of the cross bar 19 with the upper ends of the keepers 24, and the valance 13 will drop down as shown in Fig. 1.

From the foregoing it is believed that the construction, operation and advantages of the invention may be readily understood by those skilled in the art, and changes may be made in the details disclosed without departing from the spirit of the invention, as expressed in the claims.

I claim as my invention:

1. In an awning the combination of a one-piece rigid body-portion hinged by its upper end to a support, an elevating-brace pivoted at one end to the support at a point below the hinge of the body-portion and swingingly engaging the body-portion with its other end, and resilient means one end of which is connected to the upper part of the body-portion and the other end of which is connected to the swinging end of the elevating-brace the resilient means being of such a length that it is put under tension when the swinging end of the elevating-brace is lower than the pivoted end of the elevating-brace whereby the contraction of the resilient means draws the swinging end of the elevating-brace outwardly and upwardly and pushes the lower end of the body-portion outwardly.
2. In an awning the combination of a body-portion hinged at its upper end to a support, a U-shaped elevating-brace pivoted by its ends to the support the cross-bar of the U-shaped brace

swingingly engaging the lower part of the body-portion and normally holding it spaced from the support, a resilient means connected to the upper part of the body-portion and to the cross-bar of the U-shaped brace so proportioned and arranged that the resilient means shall normally hold the lower part of the body-portion in outwardly swung position and means for drawing the body-portion into a vertical position and holding it in such position.

3. In a combined awning and window-shutter the combination of an overhanging water-table to be fixed to the upper horizontal member of a window-frame, a shutter body hingedly attached under the overhanging portion of the water-table, a freely swinging valance hinged under the lower end of the shutter body, an elevating-brace pivoted to the side of the window-frame its free end swingingly engaging the pendent portion of the shutter body, resilient means attached at one end near the upper part of the shutter body and at its other end to the swinging end of the elevating-brace so proportioned and arranged as to normally keep the shutter body swung away from the window and means attached to the lower part of the shutter body whereby the shutter body may be swung to window closing position and held in such position.

EDWIN TERRY.
